UNITED STATES PATENT OFFICE.

THOMAS WALLACE McBRIDE, OF GLEN EWEN, SASKATCHEWAN, CANADA, ASSIGNOR OF ONE-FOURTH TO ABRAHAM NEILSON ATKINSON AND ONE-FOURTH TO JOHN STANLEY UREN, BOTH OF GLEN EWEN, SASKATCHEWAN, CANADA.

RODLESS WAGON-BOX.

1,128,161.

Specification of Letters Patent.

Patented Feb. 9, 1915.

Application filed September 16, 1912. Serial No. 720,553.

To all whom it may concern:

Be it known that I, THOMAS WALLACE McBRIDE, of the village of Glen Ewen, in the Province of Saskatchewan, Canada, have invented certain new and useful Improvements in Rodless Wagon-Boxes, of which the following is the specification.

The invention relates to an improved wagon box and the object of the invention 10 is to provide a strong and durable box which can be quickly placed on a wagon and which is particularly free of rods and bolts.

A further object of the invention is to provide a wagon box which will allow grain 15 or other such produce to be quickly released through the rear end.

It consists essentially in the arrangement and construction of parts hereinafter more particularly referred to and later pointed 20 out in the appended claim.

Figure 1 is a plan view of the box. Fig. 2 is a longitudinal sectional view through the same. Fig. 3 is an enlarged detailed end view of the box. Fig. 4 is a plan view 25 of the rear end of the box. Fig. 5 is a detailed vertical sectional view through the box showing the manner in which the side and end boards are connected. Fig. 6 is an enlarged detailed view of a portion of the 30 side, end and bottom boards.

In the drawings like characters of reference indicate corresponding parts in each figure.

1 represent the bottom boards of the box 35 which are securely fastened to supporting cross pieces 2, a pair of the cross pieces being connected at the ends by reinforcing boards 3 and 4.

5 represent the lower side boards which 40 rest on the bottom boards and have their sides and ends protected by metallic strips 6.

7 are similar upright channel iron members 45 permanently riveted to the side boards and having the lower ends fitted with extending threaded portions 8 which pass through the bottom boards and are fitted with nuts 9, this arrangement securing the side boards to the bottom boards.

10 are the upper side boards of the box 50 which boards have their upper and lower edges and also their ends protected by metallic strips 11 and are provided at their lower edges with countersunk plates 12

which overlap the upper edges of the adjoining side boards 5 thereby forming a grain tight joint between the side boards. The upper faces of the boards 10 are countersunk at 13 to receive if necessary a plate similar to 12 on a further side board if the wagon is to be what might be called three deck. The top side boards 10 are fitted with upright channel iron members 14 similar to those 7, the members 7 and 14 being arranged so that they are continuous when the side boards 10 are placed on those 5. All the channel members 14 with the exception of the end ones are fitted with permanent extending bars 15 which pass in to the channels of the adjoining channel members 7, 70 14 the bars affording a means for fastening the side boards together.

16 and 17 are the front end boards both of which are protected at the top and bottom by metallic strips 18 and at the ends by 75 T shaped end members 19 and 19' arranged to slide within the channels of the forward channel members 7 and 14.

20 is an end gate formed from three sections 21, 22 and 23 respectively, the sections 80 21 and 22 being butted together at 24 while the section 23 is permanently fastened to the section 22 and releasably secured to the section 21 by an I bolt 25 which when turned allows the ends of the section 23 to escape 85 and permits the end gate to buckle in the center.

The end gate is supplied with top and bottom protective pieces 26 and has the ends thereof fitted with members 27 supplied 90 each with a single laterally extending flange 28 which is arranged to pass into the end channel members carried by the lower side boards.

The end gate is prevented from rising 95 when closed by lugs 29 which are received within notches 30 located in the channel members 7. Above the end gate is an end board 31 having the upper and lower edges protected by cross strips 32 and the ends 100 fitted with T shaped members 33 similar to those 19 already referred to, which T shaped members are arranged to fit slidably into the rear pair of upright channel members 14.

All of the channel members 7 with the exception of the rear ones are fitted with levers 34 having eccentric heads 35 arranged

- when the levers are thrown down to jam against the edges of the bars 15 and hold them tightly within the channels. The levers carried by the forward pair of channel members engage with the lower front end board and prevent it from rising. The channel members 14 are also supplied with levers 36 having eccentric heads 37, the front and back pair of levers being arranged 10 to jam against the front and back end boards while the remaining levers are adapted to engage with other bars similar to those 15 in the event of a three deck box being used.
- 15 38 is a cross bar having T ends 39 arranged to slide into the channels of the channel members 14. This bar is located more or less centrally of the box and serves to strengthen the same.
- 20 It will be seen that one can quickly put this wagon box together building up as many decks as required by simply placing any number of side and end boards in position and clamping them with the levers, the 25 first side boards being fastened to the bottom boards by tightening up the nuts 9. When it is desired to release a load from the box one has simply to turn the I bolt which

action allows the end gate to open under pressure the sections 22 and 23 swinging 30 apart and the flanges 28 turning in the channels.

What I claim as my invention is:—

A wagon body of the type described, including side and end boards, said side and 35 end boards having applied thereto channel iron members equipped laterally with eccentric ended levers, additional side and end boards superposed with respect to the aforesaid side and end boards, said superposed 40 side boards also having applied thereto channel iron members, in alinement with the aforesaid channel iron members, extending bars adapted to pass into the channels of said channel members, said bar affording a 45 fastening means for said superposed side members, the latter channel iron members also being equipped laterally with eccentric ended levers, for the purpose stated.

Signed at Oxbow Sask this 14th day of 50 June 1912.

THOMAS WALLACE McBRIDE.

In the presence of—

SAMUEL R. WALLACE,
JAMES D. MURPHY.
